UNITED STATES PATENT OFFICE.

PAUL W. FURSTENBERG, OF NEW YORK, N. Y.

ADVERTISING DEVICE OR THE LIKE.

1,329,078.

Specification of Letters Patent. Patented Jan. 27, 1920.

Application filed April 21, 1919. Serial No. 291,697.

To all whom it may concern:

Be it known that I, PAUL W. FURSTENBERG, a citizen of Germany, (but having taken out his first papers with the intention 5 of becoming a citizen of the United States), residing in the city of New York, county of New York, and State of New York, have invented a certain new and useful Advertising Device or the like, of which the following is a specification.

This invention relates to the art of advertising, and is, more particularly, directed to a new article of manufacture which may be used for advertising purposes, as a show 15 card, for use in mailing, or in an office or show room, though the invention may be also employed by photographers as a picture holder or portfolio.

The object of the invention if used as an 20 advertising medium is to provide a device which may not only be readily forwarded through the mails, but which will, upon receipt, so arouse the curiosity of the addressee that he will give the article a second thought 25 and peruse the same instead of immediately depositing the same in the waste-basket, as frequently occurs with advertising matter.

A further object of the invention is to 30 provide an article of this character which will allow of the housing of a picture or the like in protected position to preclude soiling or marring of the same during use or transit, and to provide such a device which will be highly artistic and pleasing 35 in appearance.

Features of the invention other than those specified will be apparent from the hereinafter detailed description taken in conjunction with the accompanying drawings.

In the accompanying drawings I have 40 illustrated different practical embodiments of the invention, but the constructions therein shown are to be understood as illustrative only, and not as defining the limits of 45 the invention.

Figure 1 is a front view of the article shown slightly in perspective, and illustrating the preferred embodiment of the invention;

50 Fig. 2 is a view similar to that of Fig. 1, but showing portions of the article in different operative positions;

Fig. 3 is a face view of a slightly modified form of the construction;

55 Fig. 4 is a section on the line 4-4 of Fig. 3; and

Fig. 5 is a view of a further modification.

In Figs. 1 and 2 of the drawings, the invention is shown as particularly adapted for an advertising show card or calendar 60 intended to be stood in a substantially upright position on a desk or table. In this embodiment of the invention, A designates a body portion provided with a central depression or recess B adapted to normally receive a flap or door C which is hinged or pivoted to the body portion A by hinges c. A picture or illustration of any desired description depending upon the goods to be advertised, occupies the base of the recess 70 or depression B, and at least a portion of said picture is adapted to be viewed through one or a series of transparent panels D, formed in the door or flap C. The panels D are preferably of glass, celluloid or some 75 other form of transparent material, so that when the flap C is closed the picture may be readily viewed therethrough. The lower portion of the flap may be provided with a calendar or with suitable advertising matter, 80 as desired.

The picture which is placed in the recessed portion B may extend throughout said portion, or may simply occupy that part thereof which may be observed through 85 the panels D, and, in the latter case, the lower portion of the recess may be suitably printed to embody advertising matter of any desired form. In a like manner advertising matter may be positioned upon the 90 inner face of the flap C to fill that portion thereof unoccupied by the panels. To allow of ready operation of the flap C, a knob or finger piece E is preferably provided 95 thereon as shown.

In lieu of the picture which is shown as positioned in the recessed portion B, a number of catalogue sheets may be positioned therein as a pad, and the first sheet of the pad may be in the form of a picture adapted 100 to be viewed through the transparent panels D.

In the construction of Fig. 3 the device is shown as particularly adapted for use as a mailing folder. The structure disclosed 105 is the same in many respects as described with reference to Figs. 1 and 2, except that in lieu of the advertising matter on the lower portion of the flap C, this portion of the flap is adapted to contain the name and 110 address of an addressee, and thereabove a stamp may be applied so that the device

may be used for mailing without necessitating the use of a separate folder, cover, or envelop. In this construction, the flap C is shown as made integral with the body portion A, but is adapted to be folded from open to closed position, and vice versa, along the dotted line C', as will be readily understood. The flap C may be maintained closed during transit by pasting small stickers over its free edge and the adjacent edge of the body portion, or may be more readily sealed by a fastener e which extends through the flap and through the body portion, and is adapted to be spread rearwardly thereof to hold the flap in closed position. The fastener e, in practice, appears like the knob of the door C, and is in full artistic harmony with the remainder of the article.

In Fig. 5 a further modified form of the invention is shown wherein the body portion and paneled flap may partake of either of the forms of Figs. 1 or 3, but, in addition to these structures a second flap F is provided which is adapted to be folded along the line f to overlie the entire front of the body portion and flap C. This type of article is particularly adapted for use by photographers as a portrait folder or portfolio, is very artistic and has the further advantage of absolutely sealing a portrait positioned in the recessed portion B against dust.

The device of this invention may be made from any suitable material which is preferably formed from cardboard or papier mâché, whereby it is inexpensive, highly artistic, and possesses marked utility as an advertising medium, show card, a cover for catalogues or a folder in general.

Having thus fully described the invention, what I claim as new, and desire to secure by Letters Patent is:

1. As a new article of manufacture, an advertising device having a body portion provided in one of its faces with a depression adapted to receive printed and pictorial matter, a flap pivotally associated with the body portion and normally occupying the depression therein, and a transparent panel forming a portion of said flap and through which only a part of the matter delineated on the depressed portion may be observed, said flap being pivotal into open position to allow of the viewing of such matter.

2. As a new article of manufacture, an advertising device embodying a body portion having a depression in one of its faces adapted to receive printed or pictorial matter, a flap pivotally associated with the body portion and adapted to normally partake of a closed position wherein it occupies the depression of the body portion, said flap being partially cut away, whereby only a portion of the printed matter adapted to be de-

lineated on the base of the depression may be observed through the cut away portion of the flap when the flap is closed, whereas all of said matter may be observed by the opening of the flap.

3. As a new article of manufacture, an advertising device having a body portion provided with a depression in one side thereof, on the base of which depression printed or pictorial matter is adapted to be delineated, a flap pivoted to the body portion and normally occupying the recess thereof with its exposed face flush with the corresponding face of the body portion, said flap having a part thereof cut away to allow of the viewing of a part of the printed or pictorial matter, when the flap is closed, and means for normally maintaining the flap in closed position.

4. As a new article of manufacture, an advertising device having a body portion provided with a depression in one face thereof, on the base of which depression printed or pictorial matter is adapted to be delineated, a flap pivoted at one of its edges to one edge of the depression and adapted to be normally folded into a position within the depression, said flap having a cut away portion through which a portion of the printed or pictorial matter may be viewed when the flap is closed, and a second flap pivoted along one of the edges of the body portion and adapted to be folded to overlie the other flap when the latter is in closed position.

5. As a new article of manufacture, an advertising device having a body portion on one face of which printed or pictorial matter is adapted to be delineated, and a flap pivoted to the body portion and adapted to be folded to closed position to overlie the printed or pictorial matter, said flap being partially cut away to allow of the viewing of only a part of the printed or pictorial matter through the cut away portion, when the flap is in closed position.

6. As a new article of manufacture, an advertising device having a body portion on one face of which printed or pictorial matter is adapted to be delineated, and a flap pivoted to the body portion and adapted to be folded to closed position to overlie the printed or pictorial matter, said flap being partially cut away to allow of the viewing of only a part of the printed or pictorial matter through the cut away portion, when the flap is in closed position, and a second flap pivoted to the body portion and adapted to overlie the first flap when in closed position.

In testimony whereof, I sign my name to this specification.

PAUL W. FURSTENBERG.
